UNITED STATES PATENT OFFICE

2,144,374

CARBURIZING BOX

Walter G. Hoffman, Chicago, Ill., assignor to The American Brake Shoe and Foundry Company, a corporation of Delaware

Application October 21, 1937, Serial No. 170,226

11 Claims. (Cl. 263—49)

The present invention relates to carburizing boxes for use in heat treating furnaces, this application being a continuation of my application Serial No. 147,161, filed June 9, 1937, for 5 Carburizing boxes and the like.

Carburizing boxes such as disclosed in the present application, as well as other boxes used in heat treating furnaces, are subjected to severe use and handling, extremely high temperatures, 10 sudden changes in temperatures and differential heating while in the furnace. Heretofore it has been the usual practice to cast these boxes in one piece, and the same have frequently become distorted or cracked because of the alternate heating 15 and cooling during the cycle of operations, or because of the differential heating while in the furnaces, such differential heating being caused principally because one side of the boxes is subjected to the direct heat of the furnace 20 while the other side remains cooler due to being adjacent to a cooler body, such, for example, as another box being heated.

It is therefore an object of the present invention to provide a box wherein the various elements forming the same are interlocked together but movable relative to one another to prevent such cracking, twisting, warping, buckling or distortion which would otherwise take place if the elements were securely connected together or the box formed as a unitary structure.

Still another object of the present invention is to provide a box wherein the various elements thereof are interlocked together but the joint 35 therebetween being so formed as to permit longitudinal movement of certain of said elements in respect to the other and to permit other relative movement of said elements.

The present invention also contemplates the 40 idea of providing a jointed box permitting relative movement of the various elements which may, if desired, be formed with corrugations to reinforce the same.

Still another object of the present invention is 45 to provide a box in which the side walls are interlocked as above mentioned, and in which one of the open ends thereof is closed by a wall connected thereto to provide a certain amount of clearance so that the last-named wall can move 50 or expand in any direction.

The present invention also contemplates the 55 idea of providing a jointed box as above described in which the closure member for one of the open ends thereof is formed as a separate unit and connected thereto in such a way as to have rela-

tive movement with respect to the jointed side and end walls, thus eliminating cracking and warping. More in particular, the present invention contemplates such a construction in which the wall serving as a closure for the open end of the jointed box fits into and is held in place by grooves provided in the end walls and which is further formed with oppositely disposed marginal ribs embracing the side walls to limit the outward movement of the side walls in case the same bow 10 outwardly from any cause.

Other objects, features, capabilities and advantages are comprehended by the invention, as will later appear and as are inherently possessed thereby.

Referring to the drawings:

Figure 1 is a top plan view of a carburizing box made in accordance with the present invention;

Figure 2 is a fragmentary view partly in elevation and partly in cross-section taken in the 20 planes represented by lines 2—2 of Figure 1 of the drawings;

Figure 3 is a fragmentary view partly in elevation and partly in cross-section taken in the planes represented by lines 3—3 of Figure 1 of 25 the drawings;

Figure 4 is an enlarged fragmentary view in horizontal cross-section of a joint formed in the box as disclosed in Figure 1 of the drawings;

Figure 5 is a top plan view of a carburizing 30 box made in accordance with the present invention and disclosing a modified form of construction therefor;

Figure 6 is a view in cross-section taken in the plane represented by line 6—6 of Figure 5 of the 35 drawings; and

Figure 7 is a view in cross-section taken in a plane represented by line 7—7 of Figure 5 of the drawings.

Referring now more in detail to the drawings, 40 an illustrative embodiment selected to disclose the present invention is shown in Figures 1 to 4 inclusive as comprising the end walls 2 and 4 and the side walls 6 and 8 connected together at the joints 10, 12, 14 and 16 to form an interior 45 compartment 18 to receive the various articles to be heat treated, it being understood that these wall sections may be made of chromium, nickel or other appropriate heat-resistant alloy as desired. The end walls 2 and 4 are of similar construction, the same being of any desired depth and width and the central portions thereof may be corrugated as shown at 20, if desired, for reinforcing purposes. These corrugations extend 50 toward and merge with the inwardly disposed 55

portions 22 and 24, which are of rounded contour and which form in part the sides of the box and terminate in the sockets 26 and 28, respectively.

The side walls 6 and 8 are also of similar construction and may be provided, if desired, with a central corrugated portion 30 corresponding to the corrugations 20 of the end walls and which are incorporated in the side wall construction for the same purpose. This corrugated central portion merges with and terminates in the end portions 32 and 34 disposed substantially in the same plane, the same terminating to provide lugs or balls 36 and 38.

The sockets such as 26 and 28 of the end walls are formed as more particularly shown in Figure 4 of the drawings, to provide the oppositely disposed walls 40 and 42 having the restricted opening 44 at the face thereof so as to provide the interior elongated socket or recess 46, the restricted opening 44 extending between the walls 40 and 42 being of such a width as to receive the end portions such as 32 and 34 of the side walls and to provide clearance between said walls 32 and 34 and the walls 40 and 42 to permit angular movement between the walls of the receptacle. The elongated sockets or recesses 46 extend throughout the depth of the end walls 2 and 4 and are adapted to receive the lugs or elongated balls such as 36 and 38 formed adjacent the ends of the side walls 6 and 8, it being understood that these lugs or elongated balls are preferably co-extensive with the side walls 6 and 8 and cooperate with the sockets throughout their entire length. The elongated sockets are extended in a direction to provide clearance with said elongated lugs or balls to permit relative linear movement between the sides and ends of the box.

It will therefore be clearly apparent that because of the elongated ball and socket type of joints formed between the end and side walls and the clearance provided between the walls 32 and 34 and the walls 40 and 42, these walls are effectively connected together to resist pressure at any point thereon and to maintain the desired form for the box. These joints also permit relative angular and linear movement between the walls so as to prevent undesirable warping, twisting or distortion of the box which would otherwise take place if the same were of one piece or the walls rigidly connected together, due to excessive heat, alternate heating or cooling, or differential heating when these boxes are in service and used in heat treating furnaces.

In order to lock the end and side walls together and to prevent disengagement of the lugs in the sockets, locking lugs such as 48 may be provided. These locking lugs 48 are received within a suitable slot, such as 50, provided in the wall 42 of the sockets, and which slots are adapted to coincide with a slot such as 52 provided in one face of the lugs, such as 36 and 38, whereby relative displacement between the lugs and sockets is prevented and the relative movement of the walls limited to movement substantially in the direction of the disposition of said side walls 6 and 8. These locking lugs or keys 48 may be secured in place in any desired manner, but preferably by welding, such as shown at 54 in Figure 4 of the drawings.

In Figures 5, 6 and 7 of the drawings is disclosed a carburizing box or receptacle made in accordance with the present invention but varying somewhat in construction from that disclosed in Figures 1 to 4 inclusive of the drawings. This carburizing box or receptacle is

formed with the end walls 60 and 62 and the side walls 64 and 66, the same being somewhat similarly constructed as the corresponding walls in Figures 1 to 4 inclusive of the drawings, and being connected together by the elongated ball and socket type joints 68, 70, 72 and 74, each of which, as previously described, includes a socket 76 formed at the edge of the end walls and which receives the elongated ball or lugged edge 78 of the side wall, sufficient clearance being provided in the recess of the socket to permit a certain amount of relative movement between the side and end walls due to contraction and expansion without causing failure in the box, all as hereinbefore clearly described. These side and end walls may be corrugated, if desired, for reinforcing purposes, and the walls are interlocked together as by means of the transverse keys 80 fitting in aligned slots provided in the sockets of the end walls and one of the lugs at the ends of the side walls, this key being secured in place as by means of welding or the like.

The present embodiment of Figures 5, 6 and 7 includes an additional wall 82 for closing one of the open ends of the receptacle, this wall, in the illustrative embodiment, being shown as a bottom for the assembled side and end walls. As shown, the end walls 60 and 62 are each provided with the inwardly extending spaced flanges 84 and 86 extending from one socket to the other to provide the grooves 88 and 90, which grooves extend through each of the sockets of the end walls as at 92. The wall member 82 has its opposite ends formed to be received in said grooves 88 and 90 and may be of corrugated construction, if desired, for reinforcing purposes, as shown in the drawings. The wall 82 is further provided with the edge portions 94 and 96 provided with the upstanding ribs or flanges 98 and 100, respectively, which ribs embrace the side walls 64 and 66, it being noted that the side walls 64 and 66 are of less depth than the end walls 60 and 62 whereby the same rest upon the edge portions 94 and 96 of the wall 82 when the box is assembled and held together by the keys 80. The ribs 98 and 100 cooperate with the side walls 64 and 66, respectively, to limit the outward movement of said side walls in case the same bow outwardly from any cause.

It will be clearly understood, of course, that in assembling the receptacle, the wall 82 is disposed within the grooves 88 and 90 at the time the side and end walls are assembled, and that the same is held in association therewith by means of the keys 80 which cooperate with the elongated ball and socket type joints 68, 70, 72 and 74 in order to hold the assembled receptacle or box together. If desired, the wall 82 may be of flat construction or may be provided with lugs projecting from the underside to act as legs for supporting the box assembly as shown. In the illustrative embodiment of Figures 5, 6 and 7, the corrugated portions on the walls 82 serve to support the entire box assembly, the end walls resting upon the oppositely disposed edges of the wall through the flanges 84 and the side walls resting on the edge portions 94 and 96. It will be clearly understood that sufficient clearance between the wall 82 and the grooves 88 and 90 is provided in order that the wall can move or expand in any direction. This wall member is preferably cast in one piece and forms an element in a multi-part carburizing box or receptacle construction and is so arranged in respect to the other elements of the box as to permit relative

movement between the same and the side and end walls, thus preventing cracking and warping due to expansion and contraction of the parts and which would be instrumental in causing failure in the box during its use. In case the wall becomes worn, the same may be readily repaired or replaced by disassembling the entire box or receptacle by removing the locking keys 80.

10 From the above disclosure it will be quite apparent that the carburizing box disclosed in the drawings is of such a construction that relative movement between the walls thereof may take place without creating stresses in the box which would distort, crack or otherwise cause failure thereof when in use. The construction of the box is such as to compensate for expansion and contraction, and is also of such a design that one or more of the elements thereof may be replaced 15 without inconvenience and without necessitating the scrapping of the entire box. Such a construction leads to beneficial results not only from the standpoint of serviceability, but also from the standpoint of cost per unit of material 20 handled and heat treated and the cost of maintenance.

As an example, it will be evident from the foregoing specification that the term "a receptacle for use in heat treating furnaces" is intended to 30 include all uses of a receptacle embodying the invention, involving subjection of the box to high temperatures in furnaces in general, whether the treatment process be termed carburizing, heat treating, annealing or normalizing, or otherwise 35 designated. It is also to be understood that the invention includes boxes or containers for the purposes stated having their confines articulated in a manner to prevent the setting up of undesirable stresses in the structure as a whole, 40 through means permitting flexibility on vertical axes or elongation or contraction of one confine relative to another, regardless of the particular construction of articulation.

While I have herein described and upon the 45 drawings shown illustrative embodiments of the invention, it is to be understood that the invention is not limited thereto but may comprehend other constructions, arrangements of parts, details and features without departing from the 50 spirit of the invention.

I claim:

1. A receptacle for use in heat treating furnaces, comprising oppositely disposed end and side walls forming the interior compartment of 55 said receptacle, certain of said walls having an elongated socket provided adjacent an edge thereof, and certain other of said walls being provided with a lug adjacent an edge thereof cooperating with said socket to provide a joint whereby said 60 walls have sufficient relative angular and linear movement therebetween to compensate for unequal elongation of any wall with respect to another due to unequal expansion.

2. A receptacle for use in heat treating furnaces, comprising oppositely disposed end and side walls forming the interior compartment of 65 said receptacle, said walls being connected by elongated ball and socket type joints whereby said walls have sufficient relative angular and linear 70 movement therebetween to compensate for unequal elongation of any wall with respect to another due to unequal expansion.

3. A receptacle for use in heat treating furnaces, comprising oppositely disposed end and side walls forming the interior compartment of 75

said receptacle, certain of said walls having a socket formed to provide a recess adjacent an edge thereof, and certain other of said walls being provided with a lug adjacent an edge thereof cooperating with said socket, said sockets 5 being extended in directions to provide clearance with said walls whereby said walls have sufficient relative angular and linear movement therebetween to compensate for unequal elongation of any wall with respect to another due to unequal 10 expansion.

4. A receptacle for use in heat treating furnaces, comprising oppositely disposed end and side walls forming the interior compartment of said receptacle, said end walls being provided 15 with sockets having recesses adjacent the edges thereof, and said side walls being formed with lugs adjacent the edges thereof and received by said sockets, said sockets being extended in directions to provide clearance with said walls 20 whereby joints are provided therebetween permitting angular and linear movement of said lugs in said recesses and relative movement of said walls.

5. A receptacle for use in heat treating furnaces, comprising oppositely disposed end and side walls forming the interior compartment of said receptacle, said walls being connected by elongated ball and socket type joints whereby 25 said walls have sufficient relative angular and linear movement therebetween to compensate for unequal elongation of any wall with respect to another due to unequal expansion, and means for 30 interlocking said elongated balls in said sockets.

6. A receptacle for use in heat treating furnaces, comprising a plurality of wall sections forming said receptacle, means for connecting the ends of said walls to provide an articulated construction whereby said walls have sufficient relative movement therebetween to compensate for 35 unequal elongation of any wall with respect to another due to unequal expansion, and a wall for 40 closing an open end of said receptacle, and means for connecting said last-named wall to said receptacle and to provide for limited relative movement 45 between the same and said first-named wall sections.

7. A receptacle for use in heat treating furnaces, comprising oppositely disposed end and side walls forming the interior compartment of said 50 receptacle, certain of said walls having a socket provided adjacent an edge thereof, certain other of said walls being provided with a lug adjacent an edge thereof cooperating with said socket to 55 provide a joint whereby said walls have sufficient relative movement therebetween to compensate for unequal elongation of any wall with respect to another due to unequal expansion, a wall for closing an open end of said receptacle, certain of said oppositely disposed walls being provided 60 with a ledge disposed adjacent an edge thereof for receiving and supporting said last-named wall and to provide for limited relative movement 65 therebetween, and means for holding said assembled receptacle together.

8. A receptacle for use in heat treating furnaces, comprising oppositely disposed end and side walls forming the interior compartment of said receptacle, certain of said walls having a socket provided adjacent an edge thereof, certain other of said walls being provided with a lug adjacent an edge thereof cooperating with 70 said socket to provide a joint whereby said walls have sufficient relative movement therebetween to compensate for unequal elongation of any 75

wall with respect to another due to unequal expansion, a wall for closing an open end of said receptacle, means for connecting said last-named wall to said first-named walls, said means comprising oppositely arranged grooves each adapted to receive the edge of an adjacent wall and to provide clearance whereby said last-named wall is adapted to move relative to said first-named walls, and means associated with said first-named walls for holding said assembled receptacle together.

9. A receptacle for use in heat treating furnaces, comprising oppositely disposed end and side walls forming the interior compartment of said receptacle, said walls being connected by elongated ball and socket type joints wherein said sockets are provided with recesses extended in a direction to provide clearance with said elongated balls whereby said walls have sufficient relative movement therebetween to compensate for unequal elongation of any wall with respect to another due to unequal expansion, a wall for closing an open end of said receptacle, means for connecting said last-named wall to said first-named walls, said means comprising oppositely arranged grooves each adapted to receive the edge of an adjacent wall and to provide clearance whereby said last-named wall is adapted to move relative to said first-named walls, said last-named wall having marginal ribs embracing certain of said first-named oppositely disposed walls to limit the outward movement thereof, and means asso-

ciated with said first-named walls for holding said assembled receptacle together.

10 A receptacle for use in heat treating furnaces, comprising oppositely disposed end and side walls forming the interior compartment of said receptacle, said end walls being provided with sockets having recesses adjacent the edges thereof, said side walls being formed with lugs adjacent the edges thereof and received by said sockets, said sockets being extended in a direction to provide clearance with said lugs whereby joints are provided therebetween permitting movement of said lugs in said recesses and relative movement of said walls, a wall for closing an open end of said receptacle, said first-named end walls being provided with grooves adapted to receive opposite edges of said last-named wall and to provide clearance whereby said walls are adapted to move relative to one another, said last-named wall having marginal ribs embracing said first-named side walls to limit the outward movement thereof, and means associated with said first-named walls for holding said assembled receptacle together.

11. A receptacle for use in heat treating furnaces, comprising a plurality of upstanding side wall sections forming said receptacle when connected together, and means providing an articulated joint between the adjacent side wall sections, said means having means providing for limited relative angular and linear movement between said wall sections.

WALTER G. HOFFMAN.
